UNITED STATES PATENT OFFICE.

ALBERT H. EHRLICH, OF ST. JOSEPH, MISSOURI.

REFRIGERATOR DISPLAY-COUNTER.

1,227,765.

Specification of Letters Patent. Patented May 29, 1917.

Application filed February 2, 1916. Serial No. 75,661.

To all whom it may concern:

Be it known that I, ALBERT H. EHRLICH, a citizen of the United States, residing at St. Joseph, in the county of Buchanan and State of Missouri, have invented certain new and useful Improvements in Refrigerator Display-Counters, of which the following is a specification.

This invention relates to refrigerators and 10 more in particular to refrigerator display counters, and has for its object the improvement of the circulating and cooling effects of the cooling medium. Other objects will become apparent as the invention is more 15 fully set forth.

In the usual type of refrigerator counter and ice box, a certain amount of cold air circulation takes place, but such is only possible as far as the natural conditions 20 permit and may be said to be of a spasmodic nature. In this invention the circulation is created positively by means of an arrangement whereby the cold air and warm air in the refrigerator are directed definitely to 25 where a greater circulation will be created and all natural drafts reinforced. In order to bring about this action the sides or ends are suitably curved and barriers and other means provided according to a predeter- 30 mined arrangement conforming to principles under which cold and warm air act when in adjacent relation to one another.

In the accompanying drawings forming a part of this specification, Figure 1 is a vertical longitudinal view partly in section showing an embodiment of this invention. Fig. 2 is a transverse section of Fig. 1, through the central portion of the food compartment. Fig. 3 is a detail in perspective of the baffle- 40 plate used in this invention.

Similar reference characters refer to like parts throughout the drawings.

In the construction shown, the reference character 1 represents a refrigerator case 45 having suitable marble and glass panels 2, and with insulation construction as is usually used. The case is divided into two end food compartments 3 and a central ice or cooling compartment 4 which is shown with 50 ice supported on an open rack or shelf 5. The partitions 6 which separate the compartments have their upper and lower edges 7 slanting downwardly toward the ice chamber and upwardly toward the food com- 55 parts as shown in the drawings, and are disposed to permit a sufficient air space

between them and the upper and lower sides of the case. The ice chamber is provided with an apiced member 8 arranged to direct the air coming from the food compartments 3 toward the cooling medium and an upwardly directed apiced member 9 is provided at the bottom to direct the cool air and moisture toward the bottom of the food chamber. Drains 10 are provided for 60 65 egress of the water from the ice.

In each food compartment there is provided a perforated baffle plate 11 which permits the warm air to pass through but offers sufficient obstruction to cause the cooler air 70 to flow downward centrally in the chamber. The baffle plate is secured at the top of the chamber to a circular end-plate by means of screws or other fastening means and a space is provided between the ends of said plate 75 and the sides of the chamber. The ends 12 of the chambers 3 are given a large circular formation as shown and the baffle plates 11 are placed adjacent the upper ends of said curved members where they join the top of 80 the chamber. Suitable wire shelves 13 are provided to support the food. The lower wire shelf 13 is positioned above the floor of the food compartment a suitable distance so as to afford a passage way or guide-way for 85 the current of cool air entering from the cooling chamber and to direct the same onto the curved end member. This construction provides for a freer circulation of the air from the cooling chamber through the food 90 compartment and return to the cooling chamber. It should be noted that the curved end members provide substantial air spaces behind them and thus a greater amount of 95 insulation is secured for said chamber.

The general circulation of the air currents is shown by the arrows in the drawing, from which it will be seen that the cool air from the ice chamber enters the food chamber at the bottom of the latter and coming into contact with the curved end is directed onto the baffle plate. On meeting this plate the warm air, being lighter passes through the perforation in said plate while the cold air, being heavier, has a tendency to drop toward the central portion of the chamber. The warm air again enters the cooling chamber at the top of the latter as shown.

Having thus described my invention, what I claim is:

1. In a display refrigerator counter, the combination, with a case, of partitions dis-

posed in said case to form food compartments and an intermediate ice compartment, said partitions being arranged to permit air currents to flow from the upper and 5 lower portions of the compartments, a curved member disposed in the end of each of the food compartments and extending from the bottom to the top of the latter, and a perforated baffle transversely disposed in 10 the food compartments adjacent the upper end of the curved member.

2. In a display refrigerator counter, the combination, with a casing, of vertical partitions spaced from the ends of the case to 15 form food compartments and an intermediate ice compartment, each of said partitions being spaced from the top and bottom of the case to form air passages between the ice compartment and the food compartments, 20 apexed deflectors disposed in the top and bottom of the ice compartment adjacent said air passages, and a curved member disposed transversely in the outer end of each of the food compartments, said member extending

from the bottom to the top of said compartments, whereby the air currents may be guided and assisted in circulating through the chambers. 25

3. In a display refrigerator counter, the combination, with a case, of partitions 30 spaced from the ends of the case to form food compartments and an intermediate ice compartment, each of said partitions being spaced from the top and bottom of the case to form air passages between the ice compartment and the food compartments, V shaped deflectors disposed in the ice compartment adjacent the air passages, a curved plate disposed in the outer end of each of the food compartments and extending from 40 the bottom to the top of said compartments, and a perforated baffle plate transversely disposed in each of the food compartments adjacent the upper end of the curved plate. 35

ALBERT H. EHRLICH.
